UNITED STATES PATENT OFFICE.

WALTER J. McCLELLAND, OF EAST ORANGE, NEW JERSEY.

STOCKING.

Application filed March 25, 1925. Serial No. 18,314.

To all whom it may concern:

Be it known that I, WALTER J. McCLELLAND, a citizen of the United States, residing at East Orange, in the county of Essex 5 and State of New Jersey, have invented new and useful Improvements in Stockings, of which the following is a specification.

This invention relates to stockings and has particular reference to stockings of the 10 type designed to be turned or folded down at the top portion thereof. It will be recognized, however, that in many of its aspects, the invention is not limited to the manufacture of hose of that particular type, but 15 is generally applicable to the making of hose of various types.

In the use of stockings or hose of the rolled or folded down type, considerable 20 difficulty is experienced in supporting the hose upon the leg of the wearer. This difficulty has been greatly augmented by the constantly increasing practice among women to discontinue the use of a corset, thereby abolishing at the same time the well known 25 suspension supporter or garter which is ordinarily secured to the lower end of the corset. It has been heretofore proposed to support the hose by an elastic band adapted to surround the hose adjacent the upper end 30 and press the hose firmly against the leg of the wearer, and in order to retain the elastic band and the hose in a predetermined relation and eliminate relative movement therebetween, it has been proposed to permanently 35 secure the elastic band to the hose by enclosing the band within a seam formed in the upper end of the hose. This practice has many marked disadvantages, the greatest of which is that the elastic, being non-removable, quickly deteriorates and becomes 40 ineffective from the repeated subjection to water during the washing of the stocking.

A general object of the present invention is to provide an improved stocking in which 45 the disadvantages heretofore mentioned are overcome.

A further object of the invention resides in the provision of a novel stocking in which the garter or supporting means is detachably 50 connected to the stocking in such a manner as to prevent relative longitudinal movement therebetween, the garter being adapted for ready removal whenever the stocking is to be washed.

55 A further feature of the invention resides in the provision of a stocking having re-

movable ornaments or garnitures secured to the upper end thereof preferably adjacent the fold or flap.

A further feature of the invention resides 60 in the provision of a turned over stocking having a removable elastic support provided with ornaments permanently secured thereto, the support being entirely concealed by the flap of the stocking and the ornaments 65 projecting through spaced openings in the flap in a position to be clearly visible.

A further object of this invention is to provide a novel form of stocking top which is adapted to be turned over to form a cuff 70 or flap, provision being made for reinforcing or strengthening the top to facilitate the formation of the flap, at the same time preserving the artistic appearance of the 75 exposed portion of the flap.

These and other features of the invention will appear more fully from the following detailed description when read in connection with the accompanying drawings and will be pointed out in the appended claims. 80

In the drawings:

Figure 1 is a side elevation of a stocking embodying a preferred form of the invention, a portion of the flap being broken away to expose the supporting means; 85

Fig. 2 is an enlarged vertical section of the top portion of the stocking shown in Fig. 1;

Fig. 3 is an elevation of the stocking before the top has been folded; 90

Fig. 4 is a view similar to Fig. 3 showing the first folding operation; and

Fig. 5 illustrates the second folding operation by means of which the flap is formed. 95

Referring to the drawings and particularly to Figs. 1 and 2, 2 designates the main leg portion of the stocking which is preferably formed of silk, although any materials such as wool or cotton may be used if desired. The upper end of the leg portion is provided 100 with a two ply top portion 4 which may be formed integral with the leg portion in a manner hereinafter described, or may, if desired, be formed as a separate unit and attached to the leg portion by any desirable means. The top portion 4 is bent outwardly at a point substantially midway of its length to provide an overlapping cuff or flap 6. 105

Between the flap 6 and the body portion 110 of the stocking, an endless band or web 8 of suitable elastic material is provided, the

band serving to grip the leg of the wearer in a well known manner to support the stocking in a proper position. The supporting web 8 is entirely concealed from view by the outer flap 6, and does not present an unsightly or objectionable appearance.

Mounted at spaced points around the periphery of the band 8 is a plurality of ornaments or garnitures 10, the latter being preferably, although not necessarily, permanently secured to the band in any desirable manner. The flap or cuff 6 is provided at spaced points corresponding in number and location to the ornaments 10 with openings or slits 12, the ornaments being adapted to project through the slits in the flap in a position to be observed from the exterior of the stocking in the manner clearly illustrated in Figs. 1 and 2.

The ornamental device 10 may be varied in size, form, and material in accordance with the style and the taste of the individual, and, therefore, the applicant does not wish to limit himself to any particular form. As a preferred embodiment, however, the ornaments are shown as rosettes, formed of a silk ribbon, the color of the rosettes being selected to harmonize with the color of the stocking. The ornamental devices are effectively retained in position by the band 10 to which they are attached. It will be evident, however, that the removal of the ornaments from the stocking is effected simultaneously with the removal of the elastic web whenever the stocking is to be washed, thereby materially prolonging the life of the ornaments and preserving them in their original condition.

In addition to the ornamental feature of the garnitures 10, it will be noted that these elements cooperate with the supporter web 8 to hold the latter in a fixed position upon the stocking. Since the movement of the ornaments is restricted by the slits 12 through which they project, and the ornaments being attached to the web, it will be apparent that the web will be effectively prevented from creeping along the stocking or assuming an undesirable position thereon.

Referring now to Figs. 3, 4 and 5, a preferred method of forming the top of the stocking will be described. As previously stated, the major portion of the stocking is formed of silk and in fact the entire leg portion 2 is made from such material. In the manufacture of the stocking, when the knitting has progressed to a predetermined point, such as 14, depending upon the final length of stocking desired, the needles of the machine are threaded with cotton and the operation continued, producing a cotton layer A. After a predetermined width of this cotton layer is produced, the needles are again threaded with a silk thread, and a layer of silk B is formed. Finally, the

needles are changed to cotton thread again, and a relatively narrow layer of cotton C is made. The combined layers of B and C are substantially equal to the layer A in width. After the preparation of the stocking in the manner described, the top is folded inwardly about the line 16 and the edge of the top is secured to the body portion at the juncture of the leg 2 with the cotton portion A. This construction results in a two ply top portion formed on the outside by the cotton layer A and on the inside by the layers B and C of silk and cotton respectively. The two ply top thus formed is then folded outwardly substantially midway of its length to produce the flap or cuff 6 in the manner previously described. The layer B of silk is more than one-half the length of the top 4, and, therefore, will extend within the leg after the flap has been formed. In this manner, the exposed outer surface of the cuff 6 and the upper edge of the stocking will have the same finely finished silky appearance as the main leg portion of the stocking.

The unexposed cotton layer A is substantially heavier and bulkier than the silk, and, therefore, serves as a stiffening agent which both retains the shape of the flap and in addition facilitates the bending of the top to form the flap. Moreover, by forming the layers A and C of cotton or a similarly inexpensive material, the cost of the complete stocking is materially reduced.

Having described the invention, What I claim as new and desire to secure by Letter's Patent of the United States is:

1. A stocking having a main leg portion, a two ply top portion permanently secured to the leg portion, an endless elastic web adjacent the top portion and between the plies thereof, and cooperating fastening means on said web and top portion to detachably secure the web in position.

2. A stocking having a main leg portion, a two ply top portion permanently secured to the leg portion, said top portion being folded outwardly to provide an annular flap, and endless elastic web removably arranged between the flap and the leg portion, and entirely concealed thereby, removable ornamental devices projecting beyond the outer face of the top portion, and means for securing the ornamental devices to the elastic web, whereby the web and ornamental devices may be removed as a unit.

3. A stocking having a main leg portion, a two ply top portion permanently secured to the leg portion, the said top portion being folded outwardly to provide an annular flap, an endless elastic web removably arranged between the flap and the leg portion, ornamental devices upon the outer face of said flap, and means for permanently securing the ornamental devices to said web,

whereby the web and ornamental devices may be removed as a unit.

4. A stocking having a main leg portion, a two ply top portion, the said top portion being folded outwardly to provide an annular flap, the said flap being provided with a slit therein, an endless elastic web arranged between the flap and the leg portion of the stocking, an ornamental device attached to the said web, the said ornamental device being adapted to project through said slit in the flap in position to be clearly visible from the outside of the stocking.

5. A stocking formed mainly of silk and having adjacent its top a two ply band with the outer ply continuous with the leg portion of the stocking, the greater portion of the inner ply being of silk and the outer ply being of cotton, whereby when the open end of the stocking is turned down the cotton will form the inner side of the flap and be

hid within the same and the silk will form the outer side thereby giving the appearance of an all silk stocking.

6. A stocking, a main leg portion and a top portion having its lower edge permanently secured to the upper edge of said main leg portion and said top portion including an outer ply formed continuously with the leg portion and an inner ply, the outer ply being formed of a relatively bulky material and the inner ply being formed of a relatively fine material, the open end of said top portion adapted to be turned downwardly over the main leg portion to form a flap with the bulky material forming the inside of the flap and hid thereby and the exposed outside of the flap formed by the fine material.

In testimony whereof I affix my signature.

WALTER J. McCLELLAND.
